(57) **CLAIM**

The ornamental design for a bone plate, as shown and described.

DESCRIPTION

FIG. 1 is a top perspective view of a bone plate; FIG. 2 is a top view of the bone plate shown in FIG. 1; FIG. 3 is a bottom view of the bone plate shown in FIG. 2; FIG. 4 is a rear view of the bone plate shown in FIG. 2; FIG. 5 is a front view of the bone plate shown in FIG. 2; FIG. 6 is a left side view of the bone plate shown in FIG. 2; FIG. 7 is a right side view of the bone plate shown in FIG. 2; FIG. 8 is a top perspective view of another embodiment of the bone plate;

FIG. 9 is a top view of the bone plate shown in FIG. 8;

FIG. 10 is a bottom view of the bone plate shown in FIG. 9;

FIG. 11 is a front view of the bone plate shown in FIG. 9;

FIG. 12 is a rear view of the bone plate shown in FIG. 9;

FIG. 13 is a left side view of the bone plate shown in FIG. 9; and,

FIG. 14 is a right side view of the bone plate shown in FIG. 9.
